UNITED STATES PATENT OFFICE

2,282,960

SOUND HEAD

John C. Griffith, Indianapolis, Ind., assignor to
 Radio Corporation of America, a corporation
 of Delaware

Application May 19, 1939, Serial No. 274,511

3 Claims. (Cl. 179—100.3)

This invention relates to soundheads and more particularly to an improvement in the rotary stabilizer type of soundhead such as is disclosed and claimed, for example, in Loomis et al., Patent No. 2,019,147. In the said Loomis patent there is disclosed a soundhead wherein a photographic film sound record passes around a film drum with the sound track portion of the film overhanging the edge of the drum. Light from an appropriate exciter lamp is directed by an optical system through the sound track and is thereafter directed by prismatic lens to a photocell located at the opposite side of the drum. The film is drawn around the drum by a sprocket driven by an appropriate motor. The film drum is carried on a shaft mounted on ball bearings. This shaft carries at its other end a rotary stabilizer consisting of a magnesium alloy casting rigidly connected to the shaft and a flywheel freely rotatable within the casing and coupled thereto by an appropriate fluid medium, such as oil.

The present invention improves on the construction of the Loomis et al. soundhead in providing a resiliently mounted unit supporting the film drum and rotary stabilizer together with the exciter lens optical system and photocell. This unit is so mounted as to be free of soundhead vibrations produced either from the gearing or from the coupling of the soundhead with a picture projector and is constructed in an improved manner so as to secure a higher degree of precision in the relative mounting of the several parts than has been heretofore attainable, and to accomplish this at decreased manufacturing cost.

One object of the invention is to provide an improved soundhead.

Another object of the invention is to provide a soundhead which can be readily manufactured with a high degree of precision.

Another object of the invention is to provide an improved method of making the mounting for the optical system and film drum of soundheads.

Other and incidental objects of the invention will be apparent to those skilled in the art from a reading of the following specification and an inspection of the accompanying drawing in which

Figure 1 is a top view, partly in section, showing the improved features of soundhead construction; and

Figure 2 is a side view corresponding to Fig. 1 and showing the soundhead partly assembled.

Referring first to Fig. 1, the soundhead is pro-

vided with a cast body 10 which forms a casing and center plate and which is provided with supporting lugs such as 11 which serve to support the assembly including the film drum, exciter lamp, optical system, condenser lens and photocell, together with the bearings for the sound drum and rotary stabilizer, all of which will be hereinafter referred to as the reproducing unit, as distinguished from the soundhead as a whole, which includes drive mechanisms, film sprockets, etc. In the Loomis et al. patent above referred to, the various elements are mounted directly on or in the center plate of the soundhead. The present apparatus distinguishes therefrom in providing the aforesaid reproducer unit which is capable of separate fabrication and replacement. The reproducer unit includes a casting 12 which, as shown, includes a slightly conical tubular member and a more or less flat plate in a plane perpendicular to the axis of the tubular member and provided with a number of bosses. This casting 12 is first bored in the smaller end portions to provide the hollow cylindrical surfaces generally indicated at 14 and 15. This operation does not affect the intermediate portion 13 which is provided with sufficient clearance so that it needs no machining. The portions 14 and 15 are bored to the same diameter and are thereafter reamed exactly to size by means of a pilot reamer so that both of these cylindrical surfaces will be accurate as to diameter and they will be exactly in alignment with each other.

It is desired to provide the front surface of the plate portion of the casting with surfaces in a plane exactly perpendicular to the axis of the shaft 20. In order to accomplish this, the casting, after boring and reaming, is placed upon a mandrel and is rotated thereon in an appropriate machine such as a lathe and the surfaces of the bosses 16 and 17 are turned flat while the casting is being thus rotated. This insures that both of these surfaces will be in a plane accurately perpendicular to the axis of rotation. During the same operation, the surfaces of the rear bosses 8 and 9, by which the reproducing unit is secured to the soundhead, are also turned flat and in a plane accurately perpendicular to the axis of rotation.

After the foregoing operations are performed on the casting a sleeve 23, which is of such size as to be a force fit in the bore 14, is pressed into place by means of a square shouldered arbor. This sleeve 23 is pressed in to such a depth as to just accommodate the ball bearing 24 between

the end of the sleeve and the face of the surface 17. After the ball bearing 21 is placed in position, it is secured by means of a circular washer 24 which is held in place by screws 25. The shaft 20 which is made integral with the film drum may then be inserted through the bearing 21. A tubular sleeve 26, which serves as a spacer between the bearings, may then be placed over the shaft 20 and the bearing 22 put into position. The bearing 22 is held in position by the collar 27, which fits snugly thereagainst and forces the bearing against the end of the sleeve 26. The rotary stabilizer 28 is placed on the shaft after the collar 27 and may be threaded on the shaft or may be secured by a nut on the shaft bearing against the outer face of the rotary stabilizer. This clamps the rotary assembly comprising the shaft, the inner ball races and the sleeve 26 together and securely in position.

It will be apparent that the position of the film drum on the shaft 20 is accurately determined in relation to the face 17 by the positioning of the collar 23 which fixes the position of the bearing 21. The reproducer unit may then have assembled therewith the optical system bracket 29, the prism mount 30 and the photocell socket and casing 31, or these elements may be left off until after the reproducer unit is assembled with the soundhead. The reproducer unit is secured to the soundhead lugs 11 by means of bolts 32 and 33 and a bolt passing the hole 34. Between the reproducer unit and each lug there is provided an appropriate washer 36 of rubber or other resilient material. This washer has a tubular extension which passes through the hole in the lug 11 to prevent a direct contact between the bolt and the lug. A second rubber washer 35 is placed beneath the metal washer on the other end of the bolt. This arrangement thoroughly mechanically insulates the reproducing unit from the soundhead. 40

It will be apparent that these washers need not be of rubber, but may be of other appropriate material. For example, felt washers and a felt collar may be used, or one of the available synthetic materials may be used instead of rubber, such, for example, as that known commercially as "Neoprene," which is a condensation product of "Chloroprene."

I claim as my invention:

10 1. In a soundhead, a reproducing unit including a cast bracket resiliently supported in the soundhead, a rotatable assembly including a film drum, a shaft and a rotary stabilizer mounted in said bracket, an exciter lamp and optical system mounted on said bracket on one side of the said film drum and a photocell mounted on said bracket on the other side of said film drum.

20 2. The method of making a sound reproducer bracket comprising the steps of boring and reaming holes in accurate alignment in a tubular member having a planar member at one end thereof and in a plane substantially perpendicular to the axis of said tubular member, supporting said tubular member on a mandrel passing through said holes and facing off said planar member while rotating the bracket on said mandrel.

25 3. The method of making a sound reproducer bracket comprising the steps of boring and 30 reaming holes in accurate alignment in a tubular member having a planar member at one end thereof and in a plane substantially perpendicular to the axis of said tubular member, supporting said tubular member on a mandrel passing through said holes and facing off said planar member while rotating the bracket on said mandrel, and thereafter pressing a sleeve into one 35 of said holes to define the position of a bearing.

JOHN C. GRIFFITH.
